UNITED STATES PATENT OFFICE.

WILLIAM A. STARCK, OF MILWAUKEE, WISCONSIN, ASSIGNOR TO BADGER MANUFACTURING CORPORATION, OF MILWAUKEE, WISCONSIN, A CORPORATION OF DELAWARE.

DESIGN FOR AN AUTOMOBILE BUMPER.

Application filed May 13, 1922. Serial No. 2,230. Term of patent 3½ years.

To all whom it may concern:

Be it known that I, WILLIAM A. STARCK, a citizen of the United States, residing at Milwaukee, in the county of Milwaukee and State of Wisconsin, have invented a new, original, and ornamental Design for Automobile Bumper, of which the following is a specification, reference being had to the accompanying drawing, forming a part thereof.

Fig. 1 is a front elevation of an automobile bumper showing my new design;

Fig. 2 is a plan view thereof.

I claim:

The ornamental design for an automobile bumper as shown.

In witness whereof I have hereunto subscribed my name.

WILLIAM A. STARCK.
